UNITED STATES PATENT OFFICE

MORTIMER NORDEN, OF NEW YORK, N. Y., ASSIGNOR TO GENERAL OUTDOOR ADVERTISING CO. INC., OF NEW YORK, N. Y.

ILLUMINATED SIGN

Application filed February 19, 1929. Serial No. 341,230.

This invention relates to illuminated signs, and is of particular utility when embodied in advertising signs of the type characterized by luminous tubes containing noble gases such as 5 neon, helium or argon, energized by an electric current, and forming letters or other symbols.

Signs of this type as constructed at present are usually mounted in exposed positions 10 and are subject to injury by falling objects and by frost, rain, and other atmospheric agents. They tend to collect dust and are difficult to clean without liability of damage to the tube.

15 The electrical transformer required for their operation usually is housed as a separate unit and this adds to the difficulty and expense of erection.

Other disadvantages of the above mode of 20 exposed presentation of the tubes include the limitation of the effect produced to a simple outline, symbol, word, or sentence with but little contrast effect or change of color, which is recognized to be very valuable in advertising as it aids to attract attention.

An important object of the present invention is to provide a luminous tube sign which is preferably free from exposed tubing, so that liability of damage to the tube is reduced 25 to a minimum, and in pursuance of this object the luminous tube may be desirably cemented or otherwise suitable assembled with a sheet of glass or other material which is transparent or translucent in part or wholly, to 30 transmit the light from the tube, the sheet serving as a support and protective facing for the luminous tube preventing lodgment of dust on the tube, and shielding it from injurious contacts by falling objects or mis- 35 siles.

The protective glass can be cleaned easily 40 without touching the tube. The glass facing with the tube attached can be installed as the face of a box containing the electrical trans- 45 former, terminals and other operating parts, so that the entire sign can be made up as a unit and can be transported as such without injury, and installed with minimum expense.

A wider variety of luminous effects can be 50 provided than has been possible heretofore

with the exposed type of luminous tubes. For example, by providing the glass facing with a painted or frosted background, surrounding the region of the symbols occupied by the luminous tube, the words, letters or 55 other symbols can be enlarged, and their advertising effectiveness enhanced. If the glass be left clear in the immediate vicinity of the symbols, a three color effect is possible, by 60 providing luminous tubes of say reddish color and a background of another, contrasting color, with the clear glass between, which yields a very brilliant color effect.

This can be modified and changed readily, 65 without essential alteration of the sign structure, by providing auxiliary luminous tubes or lamps, within the box, and so disposed as to furnish a source of green light, or other colored light, through the clear glass portions. By using interior lamps of different 70 colors, with a suitable commutator, the different colors can be flashed at will, without disturbing the principal luminous tubes.

The glass facing, with its associated 75 luminous tube, can be attached removably to the box or container, so that the sign can be changed without removing the box, and if the facing be hinged to the box, it can be swung back readily, without removal, to permit inspection of the luminous tube, and repairs, if 80 needed, from time to time.

The above, and other features of the invention, are described and illustrated fully in the accompanying specification and drawings, and are pointed out in the claims. 85

In the drawings,

Fig. 1 is a view in front elevation of an illuminated sign in the construction of which the invention has been embodied.

Fig. 2 is a vertical transverse section of the 90 glass facing and attached luminous tube, on the line 2-2 of Fig. 1.

In the embodiment of the invention selected for illustration and description, the part designated by the reference character 95 10 is a luminous tube of the type containing a noble gas, such as neon, helium or argon, having suitable electrodes 11 and 12, and bent to constitute symbols which form the word "Unit." 100

This tube is associated with a sheet of glass 13, to the rear surface of which 14, the tube is cemented, as indicated at 15, and the glass is treated suitably, as indicated at 16, by 5 frosting or painting, or otherwise, to provide a background which is wholly or partially opaque, or relatively non-light-transmitting, according to the effect to be produced.

10 In the instance illustrated, an area of the glass around each symbol is left clear, as indicated at 17, constituting a visible enlargement of the symbols, so that the luminous tube, containing neon, yields clearly defined 15 symbols of reddish hue, surrounded by a background of black or darker hue, with an intervening clear white area around each symbol.

The glass sheet is shown as having a frame 20 hinged at 19 to a metal container or box 20, within which are disposed the usual electrical transformer 21 from which conductors 22 run out of the box to a suitable source of electrical current, and conductors 23 run 25 from the transformer to the lamp terminals 11 and 12, with a suitable controlling switch at 24. Other suitable switches and controlling devices may be provided as required.

In pursuance of another feature of the invention, an auxiliary luminous tube 25 may be adapted to furnish a luminous effect of contrasting color relatively to that of the principal tube 10, as for example a light of greenish hue, which will shine through the 25 clear portions of the glass facing around each symbol, and thus outline the symbols in green, with the red tube standing out in a relief effect.

So, also, if it is desired to produce readily 40 changeable color effects, and flash effects, other sources of light may be provided, as for example the ordinary sign lamps 26 and 27 of which those marked 26 may be of one color, and those marked 27 of another color, 45 a suitable commutator device 28 being provided to turn the lights 26 and 27 on and off alternately, yielding desirable flash effects.

It will be readily understood from the 50 above description that the illuminated sign of this invention constitutes a unit more readily installed than the conventional luminous tube signs, and that it is capable of a wider range of attractive effects, and can 55 be readily changed to substitute different symbols.

Other advantages of the device may be summarized as follows:

There is no exposed tubing, and liability 60 of damage to the tubing is reduced to a minimum. When the tubing is cemented to the glass facing the latter furnishes the luminous tubing with a rigid support which is novel in the art of constructing luminous 65 tube signs, and at the same time the glass

facing presents a surface which can be readily cleaned without liability of damage to the tubing.

The daylight value of the sign is increased considerably, and it is possible to provide 70 decorative and ornamental faces without unsightly channels and holes for the tubes.

The electrodes, wiring, transformer and other operating parts are protected from the 75 weather.

The particular structure shown is merely 80 illustrative, and other means may be adopted for carrying the invention into effect without departing from the spirit of the invention. For example, the background effect indicated at 16 may be produced by a separately formed sheet of suitable material having cut-out portions forming the symbols and acting as a mask for the rest of the background.

By the expression "translucent" used in the specification and claims, it is intended to include also a transparent material, the word "translucent" being used in the sense of light transmitting rather than translucent 90 in any restricted sense.

I claim:

1. An illuminated sign of the type having 95 symbols formed by elongated tubing, said sign being characterized by a face-plate of translucent material with portions treated to present the desired symbols and further characterized by arrangement of the luminous tubing in symbol form registering with the symbols of the facing, said tubing being secured to the rear surface of said face-plate.

2. An illuminated sign comprising a container, and a swinging closure therefor having 100 symbols formed of luminous tubing secured thereto and movable therewith, said closure comprising a face-plate of translucent material and said luminous tubing being secured to the inner surface thereof.

3. A luminous sign comprising a supporting member of translucent material, and luminous tubing secured to the rear face thereof and visible therethrough, said tubing and adjacent portions of said member being arranged to present visible luminous symbols, and means to illuminate the symbol portions of said supporting member with a color contrasting with that of said luminous tubing.

In witness whereof, I have signed this specification.

MORTIMER NORDEN. 120
